UNITED STATES PATENT OFFICE.

MADISON H. CONRAD, OF LEXINGTON, NORTH CAROLINA.

FOLDING BED.

Application filed August 12, 1921. Serial No. 491,742.

To all whom it may concern:

Be it known that I, MADISON H. CONRAD, a citizen of the United States, residing at Lexington, in the county of Davidson and State of North Carolina, have invented a new and useful Folding Bed, of which the following is a specification.

This invention aims to provide a bed which may be folded readily into couch form, novel means being provided for advancing the foldable bed frame proper, with respect to the main frame, to the end that the occupant of the bed may get the air, novel means being provided for assisting in the retraction and advancement of the bed frame, and novel means being provided for supporting the outer end of the bed frame.

It is within the province of the disclosure to improve generally and to enhance the utility of devices of that type to which the invention appertains. Within the scope of what is claimed, a mechanic may make changes in the specific form depicted and described, without avoiding the charge of infringement or departing from the spirit of the invention.

In the drawings:—Figure 1 shows in longitudinal section, a device constructed in accordance with the invention, the bed frame being extended; Figure 2 is a top plan wherein parts are broken away; Figure 3 is a fragmental top plan showing the outer end of the bed frame; Figure 4 is a front elevation, the device having been folded into couch form; Figure 5 is a vertical section, the device being folded into couch form.

The bedstead includes a main frame 1 comprising sides 2 and a back 3. Outer cleats 4 abut against the sides 2, and inner cleats 5 abut against the outer cleats 4, the inner cleats 5 being cut away at 6 to form recesses. Securing elements 7 connect the cleats 4 and 5 to the sides 2. The lower ends of radius arms 8 extend into the recesses 6 and are mounted to swing on the securing elements 7. Compression springs 9 are seated in the inner cleats 5 adjacent to the rear ends thereof.

A foldable bed frame is provided, the same including a U-shaped member 10. Pivot elements 11 connect the side portions of the member 10 with the upper ends of the radius arms 8. The rearmost pivot elements 11 have eyes 12 whereunto the upper ends of retractile springs 14 are connected,

the lower ends of the springs being secured in eyes 15 on the outer cleats 4. A head piece 16 is mounted to swing on the rearmost pivot elements 11. Outwardly offset 60 guides 17 upstand from the sides of the member 10 of the bed frame. The side portions of the member 10 of the bed frame are connected at their outer ends by a depending cross bar 18. The member 10 carries a 65 stop 91.

The bed frame embodies intermediate members 19 united by hinges 20 with the side portions of the member 10 of the bed frame. Bars 21 are secured to the under side of the members 19 and, in substance, form part thereof. The bars 21 are connected by cross slats 22 and 23.

The bed frame includes an outer member 24 which, like the inner member 10, is U-shaped in top plan. The horizontal flanges of the side portions of the member 24 are cut away (Fig. 2) at 25, and the vertical flanges are overlapped on the vertical flanges of the members 19, the said overlapped portions of the members 24 and 19 being connected by pivot elements 26. Abutments 27 are carried by the side portions of the members 19 and cooperate with the ends of the member 24, in a way to be explained hereinafter. Bars 28 are attached to the sides of the member 24 and are beveled as at 29. The bars 28 are connected by a slat 30 which is beveled at 31, to correspond with the bevel 29 of the bars 28. A cross piece 32 is attached to the outer end of the member 24 and carries a rail 33 which is longer than the cross piece 32 (note Fig. 4).

A foot piece 34 is located above the outer member 24 of the bed frame and includes side arms 35 pivoted intermediate their ends at 36 to the sides of the member 24. The lower ends of the side arms 35 are pivoted at 38 to inwardly extended links 37 95 which are pivoted at 39 to depending props 40, the props being pivotally mounted intermediate their ends as at 41, on the sides of the member 24. The sides of the member 24 carry abutments 42 wherewith the upper ends of the props 40 are adapted to engage.

Suppose that the bed is extended, as shown in Figure 1. Then, the rearmost links 8 engage the inner cleats 5 at the forward ends of the corresponding recesses 6, 110 and downward movement of the member 10 is prevented. The rear ends of the mem-

bers 19 engage the forward ends of the member 10 and the rear ends of the member 24 engage the abutments 27, the outer end of the bed frame being supported on the 5 props 40. One of the foremost links 8 engages the stop 91.

When the bed frame is to be folded, the head piece 16 is swung in the direction indicated by the arrow A in Figure 1, and the 10 foot piece 34 is swung in the direction of the arrow B, these parts then serving to hold the mattress (not shown) on the bed frame. When the foot piece 34 is swung in the direction indicated by the arrow B, 15 the links 37 carry the props 40 into approximate parallelism with the side portions of the outer U-shaped member 24.

The bed frame is thrust inwardly, the 20 radius arms 8 swinging inwardly, the inner member 10 of the bed frame resting on the cleats 5, and the springs 9 being compressed by the member 10 in its downward and inward movement. At this point, the operation 25 of the springs 14 and 9 may profitably be dwelt upon. When the bed frame is retracted, the springs 14 are under tension, and when the operator starts to pull the frame forward, the springs 14 aid in the forward movement of the frame. The 30 springs 9, it will be recalled, are compressed by the member 10 of the bed frame, when the frame is retracted, and the springs 9 constitute an important means supplementary to the springs 14, for initiating the 35 outward movement of the bed frame into the position shown in Figure 1. Especial attention is directed to the fact that the radius arms 8 carry the head piece 16 outwardly and forwardly, away from the back 3 of the main frame. As a consequence, the 40 head of the occupant of the bed is located well toward the front of the main frame 1 and not adjacent to the back 3, it being clear that the occupant of the bed can get 45 more air and better air, owing to the construction and operation above described. In other words, the head of the person who is recumbent on the bed is not thrust back into the pocket or compartment formed by 50 the sides 2 and the back 3.

When the member 10 is folded backwardly into the position above described, and shown in Figure 5, the members 19 are 55 swung backwardly and rest upon the guides 17, the hinges 20 permitting the necessary swinging movement. The outer member 24 upstands and rests against the back 3, the structure then being converted into a couch, the cross bar 18 giving a finish to the lower front portion of the couch as will be evident from Figures 5 and 4, the rail 33 extending 60 between the sides 2 at the extreme rear portions thereof. The slats 22 are adapted to support a seat (not shown) and the member 24 is adapted to support a back (not 65

shown). The slat 30 is disposed above the slat 23 and defines the angle between the back and the seat, the back being given the proper pitch, because the bars 28 are beveled at 29 and because the slat 30 is beveled as 70 at 31.

I claim:—

1. In a bedstead, a main frame comprising sides and a back, a bed frame foldable with respect to the main frame and including 75 an inner member, radius arms pivotally supported at their lower ends upon the main frame and pivoted at their upper ends to the inner member, the radius arms being upwardly and forwardly inclined when the bed 80 frame is advanced, means for limiting the forward movement of the radius arms, a retractile spring extended between the inner member and one of the sides of the main frame, the spring being upwardly and rearwardly inclined, whereby the spring will 85 be tensioned continuously throughout the entire interval during which the inner member moves rearwardly and a substantially vertical second spring compressed between 90 the inner member and the main frame when the bed frame is retracted, the second spring facilitating the upward movement of the bed frame initially, when the operator starts the forward movement of the bed frame, 95 and at a time when the first specified spring is so nearly in a horizontal position that it has but little effect in moving the inner member upwardly.

2. A bed comprising a main frame; a bed 100 frame including an inner member, an outer member, and an intermediate member located between the inner and outer members and hinged thereto, the intermediate member being carried and supported by the inner 105 and outer members, a foot piece pivoted to the outer member; a prop pivoted to the outer member; means for connecting the prop operatively with the foot piece; a head piece pivoted to the inner member; and radius arms pivoted to the main frame and to the inner member, the inner member being movable into retracted position on the radius arms, the intermediate member being foldable to lie above the inner member, 110 and the outer member being foldable into a position approximately at right angles to the intermediate member, the head piece being foldable to lie between the inner and intermediate members, and the foot piece 115 being foldable into a depending position behind the outer member, the main frame constituting a support for the outer member, the main frame, the outer member and the intermediate members cooperating to form 120 a couch.

3. A bed comprising a main frame including sides and a back; a bed frame including an inner member; radius arms pivoted to the main frame and to the inner member and 130

constituting means whereby the inner member may be moved rearwardly; a cross bar depending from the inner member and adapted to be received between the sides of 5 the main frame when the inner member is retracted, and to be located adjacent to the forward edges of the sides, the cross bar being so constructed as to occupy the space below the forward edge of the inner member 10 and to give a finished appearance to the bed when the inner member is moved rearwardly; an intermediate member hinged to the inner member and adapted to be folded backwardly to overlie the inner member; a 15 cleat carried by the intermediate member adjacent to the outer end thereof; an outer member hinged to the intermediate member

and adapted to be disposed in upstanding relation to the intermediate member when the intermediate member is folded backwardly 20 and rearwardly; and a cleat carried by the outer member, the cleats coacting to define an angle between the outer and intermediate members when the outer member is disposed in upstanding relation to the intermediate 25 member.

In testimony that I claim the foregoing as my own, I have hereto affixed my signature in the presence of two witnesses.
